(57) **CLAIM**

The ornamental design for lighting fixture, as shown and described.

DESCRIPTION

FIG. 1 is a front isometric view of a lighting fixture according to a first embodiment of the design;

FIG. 2 is a rear isometric view of the lighting fixture of FIG. 1;

FIG. 3 is a side view of the lighting fixture of FIG. 1;

FIG. 4 is a front view of the lighting fixture of FIG. 1;

FIG. 5 is a rear view of the lighting fixture of FIG. 1;

FIG. 6 is a front isometric view of a lighting fixture according to a second embodiment of the design;

FIG. 7 is a rear isometric view of the lighting fixture of FIG. 6;

FIG. 8 is a side view of the lighting fixture of FIG. 6;

FIG. 9 is a front view of the lighting fixture of FIG. 6; and,

FIG. 10 is a rear view of the lighting fixture of FIG. 6.

The broken lines in the drawings are for illustrative purposes only, and do not form part of the claimed design.
